UNITED STATES PATENT OFFICE.

WARREN H. LAMSON, OF LYNN, MASSACHUSETTS.

PENCIL-SHARPENER.

SPECIFICATION forming part of Letters Patent No. 334,242, dated January 12, 1886.

Application filed January 12, 1885. Serial No. 152,646. (No model.)

To all whom it may concern:

Be it known that I, WARREN H. LAMSON, of Lynn, in the county of Essex and Commonwealth of Massachusetts, have invented certain Improvements in Pencil-Sharpeners, of which the following, taken in connection with the accompanying drawings, is a specification.

This invention relates to pencil-sharpeners, and the nature thereof is fully described hereinafter, and specifically pointed out in the claims.

Referring to the drawings, Figure 1 is a perspective view of the pencil-sharpener and its handle, the two being represented as detached, but the manner of combining the two is indicated in this view by dotted lines. Fig. 2 is a vertical cross-section of the sharpener, made on dotted line *xx*. Fig. 3 is a vertical longitudinal section of the sharpener, and illustrates the operation of sharpening the pencil. Fig. 4 is a sectional view of the sharpener and illustrates the operation of discharging a broken lead therefrom.

The exterior formation of the pencil-sharpener A is fully illustrated in Fig. 1 of the drawings. Said sharpener-case A is composed of metal or other suitable material, and is provided with an end bore or chamber, made conical in form, or similar to the shape intended to be given to the pointed pencil. Said case is further provided with a knife, *a*, which is fixed in the chamber of the case in the usual way, and which operates to trim the pencil while the case is being revolved. The chip removed by the knife escapes outward through a suitable slot or throat in the case A, as fully illustrated in Fig. 3. At the rear end of said chamber is a stop, *e*, which is represented as made integral with the case A; but it may, if desired, be a distinct piece of metal fixed into the case A at this point. In the operation of pointing a pencil the pencil is pushed into the chamber in the case A until the end of the sharpened lead comes against this stop *e*, as in Fig. 3.

I am aware that a stop to arrest the inward progress of a pencil is not broadly new in a pencil-sharpener; but the stop *e* in my sharpener is formed so as to leave a part of the end face of the pencil-lead exposed, in order that it may be reached by the end of a pointer, *H*, and pushed backward, as illustrated in Fig. 4.

To this end the stop *e* may be formed with one flat side, or it may have a very small central hole, through which the pointer may be introduced to the end of the lead. The case A in rear of the stop *e* is solid and conical or tapering in form, thus forming a suitable tang to fit a corresponding bore in the handle C. The case A is also provided with a small hole, *h*, extending from the inner end of the pencil-chamber outward to the rear side of the case. This opening *h* allows the lead filings taken off the pencil to escape outward, and thus the sharpener is kept from clogging.

In close proximity to the hole *h* is an inclined hole, *f*, the inner end of which leads to that point on the end of the pencil-lead not covered by the stop *e*, so that a pointer pressed into this hole will be guided directly to the end of the pencil-lead, and thus facilitate the operation of dislodging a broken lead from the chamber.

I am aware that the pointer may be operated down through the hole *h*, but not so easily as through the hole *f*.

For convenience and neatness in operation, the sharpener may be connected with a handle, C, or it may be inserted into the end of a revolving shaft and operated by a suitable crank.

In most cases the friction between the walls of the shaft and the tang of the sharpener will be sufficient to hold the sharpener from turning. In some cases it might be found to slip, however, and to obviate this I provide the sharpener with a pin, *n*, which is fixed into the tang of the sharpener, and is adapted to pass into the slot *p* in the chamber of the handle-shaft, as indicated in dotted lines in Fig. 1. The slot *p* being curved, as shown, prevents the sharpener not only from turning, but also from moving longitudinally outward.

I claim—

1. A pencil-sharpener consisting of a case, A, having an inner conical bore, a cutting-knife secured therein, an exit-passage for the chips or shavings, a stop, *e*, arranged at the rear of the conical bore, and an exit-opening leading from said conical bore, substantially as described.

2. A pencil-sharpener consisting of a case, A, having an inner conical bore, a cutting-knife secured therein, an exit-passage for the chips or shavings, a stop, *e*, arranged at the

2 rear of the conical bore, a vertical exit-opening for the lead filings, and an inclined passage, *f*, substantially as and for the purpose described.

3. In a pencil-sharpener of substantially the construction described, the case A, having the described longitudinal bore to receive the pencil end, an exit, *h*, and an inclined passage, *f*, the rear end of said sharpener being formed

into a conical tang and provided with pin *n*, in combination with a suitable handle, C, having slot *p* to receive the pin *n*, and a chamber to receive the tang of the sharpener. 10

W. H. LAMSON.
